FINDING FOR A CLASP

Carl Pearson, Pawtucket, R. I., assignor to J. & L. Tool Company, Attleboro, Mass., a firm composed of Emil L. Johnson and Olof Lundsten

Application February 11, 1933, Serial No. 656,278

7 Claims. (Cl. 24—252)

This invention relates to a finding for a clasp of the type more particularly designed for use as a dress ornament and has for one of its objects the provision of a device comprising a minimum number of parts that assembling operations may be simplified.

Another object of the invention is the provision of a construction having a resilient opening action or closing action depending upon the position of the relatively movable parts, which resilient action will not be damaged by excessive opening of the parts as may occur in other similar clasps.

Another object of the invention is the limiting of the flexing of the spring such that the spring cannot be moved excessively to set the same at the bend and destroy the resilient action for which it is set.

Another object of the invention is the provision of a spring which may be easily reset to increase the tension if desired.

With these and other objects in view, the invention consists of certain novel features of construction, as will be more fully described, and particularly pointed out in the appended claims.

In the accompanying drawing:

Fig. 1 is a perspective view of the device and illustrating by dotted lines the position of an ornament with relation thereto.

Fig. 2 is a perspective view of the back jaw.

Fig. 3 is a perspective view of the mounting member which is pivotally secured to the back jaw.

Fig. 4 is a perspective view of the mounting member looking at the same from the opposite direction from that shown in Fig. 3.

Fig. 5 is a sectional view showing the back jaw partly opened and the spring as being limited in its flexing movement.

Fig. 6 is a perspective view showing the mounting member as attached to an ornament and the back jaw as being positioned in place after such soldering has taken place.

Fig. 7 is a section view of the members in assembled position.

It is usual to sell to an ornament maker a so-called "finding" for a clasp for securing the finding to the ornament, the assembly being then sold as a dress clip for mounting upon dresses, hats or for other ornamental purposes. Findings of this character are frequently sold unassembled that the ornament mounting member may be secured to an ornament and the back jaw then assembled with the mounting member. Many clips utilize a separate spring positioned between

the mounting member and the back jaw which requires the assembly of two parts after the mounting member is soldered to the ornament, and to simplify this assembly I have caused the spring to be formed as an integral part of the mounting member. Frequently, also after the parts are assembled a flexing movement of the jaw to a position wider open than is intended will strain the spring and prevent its proper operation after such straining, and by reason of its location the spring cannot be reset if stronger tension is desired, and I have avoided these undesirable features by folding over a spring to lie between the mounting member and the jaw member so that the spring will be limited in its movement and cannot be flexed beyond a certain desired position; also by reason of my arrangement of the spring, the end portion of the spring is accessible for changing the shape of the bend thereof to adjust its tension, and the following is a more detailed description of the present embodiment of this invention illustrating the preferred means by which these advantageous results may be accomplished.

With reference to the drawing, 10 designates the back jaw which is provided with prongs 11 adjacent one end forming a work engaging portion at the front end which cooperates with the back of the ornament or other device to which the jaw is attached to grip a piece of fabric or the like between it and the ornament. At the opposite or rear end of the jaw I provide laterally extending trunnions 12 and a flange 13 extending at an angle to the plane of the general extent of the jaw 10 for engagement with the spring on the rear side of the pivot as will be more fully explained.

The mounting member 14 is provided with a surface 15 for soldering to an ornament 16. Ears 17 are bent up from the portion 15 of the mounting member to pivotally receive in their openings 18 the trunnions 12 of the back jaw. The stock forming the surface 15 is extended forwardly and folded as at 19 to provide a tongue 20 extending between the ears 17 and providing a resilient spring portion with which the flange 13 and the jaw member engages on the opposite side of the pivot 12 from the fold 19. The point of engagement is such that there is a tendency to swing the ornament and work-engaging surface of the back jaw together to firmly grip and clamp a piece of fabric or the like between them.

By reason of the tongue 20 being folded over beneath the work-engaging surface of the mounting member and being of a certain predetermined

length the end of the tongue 21 is so positioned that it will engage the undersurface of this mounting portion, and this end will limit the flexing of the tongue to such an extent that it cannot be strained by reason of excessive flexing or movement of the parts about their pivot, but will limit this undesirable flexing as shown in Fig. 5. Also by reason of the fold opening rearwardly and the accessibility of the end portion 21 of the tongue, a blunt edged instrument may be inserted and the fold 19 sprung open to increase the tension on the spring when such action is desired.

When the mounting member and jaw are sold separate the ears 17 of the mounting member will be spread apart as illustrated in Fig. 6 so that when the mounting member, as shown in Fig. 6, is soldered to the ornament 16 the trunnions of the back jaw may be inserted first one in one ear, and then the other in the other ear or in line with the opening 18 of the other ear after which these ears are folded toward each other to receive the trunnions 12 and cause the members to assume the pivotal relation desired.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A device of the character described comprising a pair of members, means for pivotally securing said members together, a resilient tongue folded from one member to extend between said member and engage the other member on the opposite side of the pivot from said fold and nearer the tongue carrying member than the pivot when in working position to tend to swing said members about said pivot in one direction.

2. A finding for a clasp comprising a jaw member, an ornament mounting member, means for pivotally securing said members together, a resilient tongue folded from one member to extend between said members, and a flange on the other member engaging said tongue on the opposite side of the pivot from said fold and nearer the mounting member than said pivot when in working position and serving to tend to swing said members about said pivot in one direction.

3. A finding for a clasp comprising a jaw member, an ornament mounting member, means for pivotally securing said members together, a resilient tongue folded from said mounting member to extend between said members, and a flange on the jaw member engaging said tongue on the

opposite side of the pivot from said fold and nearer the mounting member than said pivot when in working position and serving to tend to swing said members about said pivot in one direction.

4. A finding for a clasp comprising a jaw member having a work engaging end portion, an ornament mounting member, means for pivotally securing said members together, said mounting member being folded to extend back upon itself and between said members to provide a resilient tongue extending away from the engaging end portion of the jaw member and opening outwardly from the rear thereof and engaging the jaw member nearer the mounting member than said pivot to move the members about said pivot in one direction.

5. A finding for a clasp comprising a jaw member having a work-engaging portion extending inwardly from one end, trunnions extending laterally at the other end, a mounting member of a length incapable itself of serving as a jaw and for attachment to an ornament or the like, ears on said mounting member pivotally receiving said trunnions, a tongue integral with said mounting member and folded therefrom and extending between said members and engaging said jaw member on the opposite side of the pivot from said fold when in working position to tend to swing said member about said pivot in one direction.

6. A finding for a clasp comprising a jaw member having a work-engaging portion extending inwardly from one end, trunnions extending laterally at the other end, a mounting member of a length incapable itself of serving as a jaw for attachment to an ornament or the like, ears on said mounting member pivotally receiving said trunnions, a tongue integral with said mounting member and folded therefrom and extending between said members, a flange on said jaw member folded therefrom to engage said tongue on the opposite side of the pivot from said fold when in working position whereby the members are urged in one direction about said pivot.

7. A finding for a clasp comprising a jaw member, an ornament mounting member, means for pivotally securing said members together, a resilient tongue folded from one member to extend between said members, and a flange on the other member engaging said tongue and serving to swing said members about said pivot in one direction, the tongue being of a length to cause its free end to engage said mounting member to limit its flexing movement under pressure of said flange when the jaw is being opened.

CARL PEARSON.
